UNITED STATES PATENT OFFICE

PAUL A. BANCEL, OF MONTCLAIR, NEW JERSEY, ASSIGNOR TO INGERSOLL-RAND COMPANY, OF JERSEY CITY, NEW JERSEY, A CORPORATION OF NEW JERSEY

CONDENSER

Application filed December 18, 1929. Serial No. 414,962.

This invention relates to condensers, but more particularly to a flexible joint adapted to be interposed between sections of the condenser casing.

5 One object of the invention is to permit of expansion and contraction of the elements to which the condenser is attached, such as turbine nozzles without necessitating the use of flexible couplings at the turbine nozzles. 10 The condenser of this invention is particularly adapted for use with a double flow turbine having a central steam inlet in which the steam enters at a very high temperature for instance 700°-750° F. This 15 means that the center part of the turbine barrel is at a corresponding temperature. On a single flow turbine, the exhaust end is dowelled and movement due to changes in temperature occurs at the steam inlet end on 20 some form of greased guides. This, of course is not possible with a double flow turbine and movement must be taken up laterally by one or both of the exhaust nozzles, the center being dowelled. The present construction 25 permits of bolting up directly to the steam nozzles and has the supplementary advantage of permitting free movement of the shell when the tubes expand and contract longitudinally. Furthermore, in the preferred 30 construction there are no supports under the condenser and therefore it is impossible for any strains in any direction either lateral or vertical to be put upon the turbine nozzle.

Other objects will be in part obvious and 35 in part pointed out hereinafter.

In the drawings illustrating the invention and in which similar reference characters refer to similar parts,

40 Figure 1 is a longitudinal sectional elevation of a condenser constructed in accordance with the practice of the invention, and

Figure 2 is a transverse view of a detail taken through Figure 1 on the line 2—2 looking in the direction indicated by the arrows.

45 Referring more particularly to the drawings, A designates a casing comprising in this instance two sections B and C, each of which has an inlet opening D for steam and an outlet opening E for condensate. The casing A is shown as being supported by noz-

zles F which may form a part of a center inlet turbine (not shown) and through which the steam from such turbine or similar machine flows into the sections B and C.

The condenser may be of the single pass 55 type and is provided with tubes G which extend longitudinally of the casing and transversely of the direction of steam flow. The tubes G are supported intermediate their ends by support sheets H and are fixedly secured at the ends to tube sheets J, as for instance by expanding the ends of the tubes 60 into the tube sheets.

In the construction shown, the tube sheets J also serve as closures for water boxes K and 65 L which may be substantially symmetrical. One box, as for instance the box L, may serve as an inlet box into which the cooling water is introduced through inlet openings O. The box K serves as an outlet box having outlet 70 openings P through which the cooling water flows from the water box K. Both boxes K and L may be divided into two compartments by walls Q interposed between the openings 75 of the boxes.

In accordance with the present invention, means are provided for permitting the expansive and contractile movement of the turbine nozzles F and corresponding relative movement of the casing sections. This means 80 comprises a flexible band R interposed between the adjacent ends of the sections B and C which are suitably spaced with respect to each other. The band R thus forms a portion of the casing A. In cross section the 85 flexible band R may be substantially U-shaped. The straight legs S of the band are adapted to lie flush against the ends of the sections B and C and may be conveniently clamped thereto by clamping rings T which 90 may be secured to the ends of the sections in any suitable way.

Similarly, between the outer ends of the sections B and C and the tube sheets J are interposed flexible bands R which are held 95 securely in position by clamping rings T.

From the foregoing it will be seen that any expansion or contraction which may take place between the nozzles F will not cause strains in the condenser shell. Likewise, ex- 100

pansion and contraction of the sections B and C and the turbine nozzles F will not impose a strain on the tubes G, since any lateral movement of the sections B and C will react 5 only on the flexible bands R.

Inasmuch as the tubes are constantly filled with cooling liquid and are of different material they will not expand or contract in the same degree as the portions comprising the 10 casing of the condenser. Due to this fact it is desirable that the means, such as the tube sheets J to which the tubes are fixed be capable of adjusting their positions relatively to the sections and also relatively to each other. 15 Otherwise the joints between the tubes and the tube sheets may become bent or loosened or the tubes may become bent or broken, particularly where they have been previously weakened by corrosion. In order therefore 20 to enable the water boxes K and L to adjust their positions to compensate for any variation in the lengths of the tubes, said water boxes are provided with separate supporting means in the form of bearings U which in 25 turn may be mounted on supports V located at a lower level than the means, such as a floor (not shown) whereby the turbine is supported.

The bearings U may be in the form of plates 30 provided at opposite ends with side walls W having integral introverted flanges X which overlie lateral flanges Y carried by the water boxes K and L. Means, such as rollers Z, are interposed between the bearings U and 35 the bottom of the water boxes to support the weight of the water boxes and also to enable said boxes to move readily with respect to the sections in accordance with the degree of expansion or contraction of the tubes G. 40 In practice the present invention has been found to function in an unusually efficient manner. It enables the casing A and the tubes G to expand in variable degrees without subjecting one element to the strains induced 45 by the movement of another element.

I claim:

1. In a surface condenser, a casing comprising a plurality of sections each having an inlet for steam, and a flexible joint between the sections to permit relative movement of the steam inlets.

2. In a surface condenser, a casing comprising a plurality of sections adapted to be suspended from the same support, each section having an inlet for steam, and a flexible joint between the sections to permit relative movement of the steam inlets.

3. In a surface condenser, a casing comprising a pair of sections spaced with respect 60 to each other and adapted to be suspended from a common support, and a flexible joint connected to adjacent ends of the sections and forming a portion of the casing.

4. In a surface condenser, a casing comprising a pair of sections, water boxes at the

outer ends of the sections, a flexible joint between the sections to permit relative movement of the sections and flexible joints between the sections and the water boxes to permit movement between the sections with 70 respect to the water boxes.

5. In a surface condenser, a casing comprising a pair of sections, water boxes at the outer ends of the sections, tube sheets carried by the water boxes, cooling tubes in the casing and connected at their ends to the tube sheets, a flexible joint between the sections to permit movement of one section with respect to another, and flexible joints between the sections and the tube sheets to permit relative movement of the tubes and the 80 sections.

6. In a surface condenser, a casing comprising a pair of sections, water boxes at the outer ends of the sections, tube sheets carried by the water boxes, cooling tubes in the casing and connected at their ends to the tube sheets, a flexible joint between the sections to permit relative expansive and contractile movement of one section with respect to another, flexible joints between the sections and the tube sheets to permit of variable degrees of expansion of the tubes and the sections, and means disassociated from the casing and the casing support to support the water boxes.

7. In a surface condenser, a casing comprising a pair of sections, water boxes at the outer ends of the sections, tube sheets carried by the water boxes, cooling tubes in the casing and connected at their ends to the tube sheets, a flexible joint between the sections to permit expansive and contractile movement of one section with respect to another, flexible joints between the sections and the tube sheets to permit of variable degrees of expansion of the tubes and the sections, bearings disassociated from the casing and its support to support the water boxes, and means interposed between the water boxes and the bearings to permit of endwise movement of the water boxes on the bearings.

8. In a surface condenser, a casing comprising a pair of sections, water boxes at the outer ends of the sections, tube sheets carried by the water boxes, cooling tubes in the casing and connected at their ends to the tube sheets, a flexible joint between the sections to permit expansive and contractile movement of one section with respect to another, flexible joints between the sections and the tube sheets to permit of variable degrees of expansion of the tubes and the sections, bearings disassociated from the casing and its support to support the water boxes, and rollers interposed between the water boxes and the bearings and movable relatively to both to permit of endwise movement of the water boxes on the bearings.

9. In a surface condenser, a casing com-

prising a pair of sections adapted to be suspended from a common support, each section having an inlet for steam, water boxes at the outer ends of the sections, a flexible joint between the sections, and flexible joints between the sections and the water boxes to permit movement of the sections relative to each other and to the water boxes.

- 5 10. In a surface condenser, a casing comprising a pair of sections, water boxes at the outer ends of the sections, tube sheets forming closures for the water boxes, cooling tubes in the casing connected at their ends to the tube sheets, a flexible connection between adjacent ends of the sections, and flexible connections between the sections and the tube sheets to permit of relative expansion of the casing sections and the cooling tubes.
- 15 20. 11. In a surface condenser, a casing comprising a pair of sections, water boxes at the outer ends thereof, a flexible joint between said sections to permit of relative movement of the sections, flexible joints between the sections and the water boxes to permit movement therebetween, and means disassociated from the casing and the casing support to support the water boxes.
- 25 30. 12. In a surface condenser, a casing comprising a pair of sections in endwise relationship flexibly connected at their adjacent ends, water boxes flexibly connected to their outer ends, and means independent of the casing to support the water boxes.
- 35 40. 13. In a surface condenser, a casing comprising a pair of sections in endwise relationship flexibly connected at their adjacent ends, steam inlets into each section, water boxes flexibly connected to their outer ends and means independent of the casing for supporting the water boxes.

In testimony whereof I have signed this specification.

PAUL A. BANCEL.
